UNITED STATES PATENT OFFICE

EARL R. SWANSON, OF CHICAGO, ILLINOIS, ASSIGNOR TO CHICAGO-CLEVELAND CAR
ROOFING COMPANY, OF CHICAGO, ILLINOIS, A CORPORATION OF DELAWARE

RAILWAY CAR

Application filed July 31, 1930. Serial No. 472,168.

My invention relates to railway cars and more particularly to means associated with the roof structure of railway cars of the box-type adapted to cooperate with load lifting devices whereby automobiles and other similar lading may be moved into or out of the car or raised within the car.

A principal object of the invention is to provide simple and rugged means cooper-
able with load lifting devices associated with the roof structure in such manner as to occupy a minimum amount of the lading carrying space of the car.

A principal feature of the invention con-
sists in providing a car having upstanding carline portions with a longitudinally dis-
posed beam extending between the carline portions in overlapping relation to the outer face of an adjacent roof sheet, a member being disposed beneath the roof sheets and rigidly secured to the beam and constituting means for supporting a load lifting device.

Another feature of the invention consists in providing the car with a longitudinally extending beam arranged in overlapping relation to an adjacent roof sheet and in associating therewith a member which extends transversely of the car beneath the roof sheet and is rigidly secured to the beam, a portion of the member being spaced from the roof sheet to receive a load lifting device.

A further feature of the invention con-
sists in providing a car having upstanding carline portions with a longitudinally ex-
tending beam of inverted channel-shape, the beam having laterally projecting flanges secured in overlapping relation to the outer face of an adjacent roof sheet, a member being rigidly secured to the flanges of the beam beneath the roof sheet and constituting means for supporting a load lifting device.

A still further feature of the invention consists in providing a car having upstanding carline portions with a plurality of longitudinally extending beams disposed above the roof sheets and arranged on op-
posite sides of the carline portions, the ad-
joining ends of adjacent beams being con-

nected by means extending beneath the carline portions and forming therewith structures of box-like section, each of said means being adapted to serve as a support for a load lifting device.

Other and more specific features of the invention residing in advantageous forms, combinations and relations of parts will hereinafter appear and be pointed out in the claims.

In the drawings illustrating preferred embodiments of the invention,

Figure 1 is a longitudinal sectional view of the upper portion of a railway box car embodying one form of the invention.

Figure 2 is a fragmentary sectional view taken on line 2—2, Figure 1.

Figure 3 is an enlarged fragmentary sec-
tional view taken on line 3—3, Figure 2.

Figure 4 is an enlarged fragmentary sec-
tional view taken on line 4—4, Figure 1.

Figure 5 is a sectional view taken on line 5—5, Figure 4.

Figure 6 is a view corresponding to Fig-
ure 1, illustrating a modified form of the invention.

Figure 7 is a fragmentary sectional view taken on line 7—7, Figure 6.

Figure 8 is an enlarged fragmentary sec-
tional view taken on line 8—8, Figure 7.

Figure 9 is a fragmentary sectional view taken on line 9—9, Figure 8.

Referring more particularly to the draw-
ings, 1 indicates the side plates and 2 the end plates of the roof structure of a railway box car of any suitable design. The roof sheets, designated by the reference numeral 3, may advantageously extend continuously from one side of the car to the other and at their eaves edges they are flanged downwardly as at 4 for attachment to adjoining portions of the side plates by rivets 5.

Instead of employing separable carlines for rigidifying the roof structure, the adjoining portions of adjacent roof sheets are each provided with an upwardly extending leg 6 which terminates in a laterally projecting flange 7 spaced considerably above the major portion of the roof sheet. The flanged portion 7 of adjacent roof sheets are overlapp-

pingly secured by rivets 8 whereby the roof is formed with upwardly extending portions which in effect constitute and function as carlines. Since these carline portions may 5 advantageously decrease progressively in depth from adjacent the ridge of the roof the flanged portions 7 of each roof sheet as it approaches the eaves edges thereof is formed with downturned portions 9 which 10 overlap the adjacent leg 6 of the adjoining roof sheet. To connect the end roof sheets with the side plates they may advantageously be formed with downturned flanges 10 for attachment by rivets 11 to adjoining 15 portions of the end plates.

As is usual in box car construction, the roof is provided with a longitudinally extending running board formed of a plurality of planks 12. At their ends the planks 20 12 are rigidly connected together and to the end plates by brackets 13 while intermediate their ends they are connected together and to the carline portions by angle shaped brackets 14.

25 Extending longitudinally of the car above the roof sheets and respectively disposed on opposite sides of the carline portions are beams 15. Each of these beams is formed with a web portion 16 and downwardly extending legs 17 terminating in oppositely disposed laterally extending flanges 18 arranged in overlapping relation to the outer face of an adjacent roof sheet. The portions of the beams adjacent the carline portions 30 are formed with upturned flanges 19 adapted to overlap the outer faces of the legs 6 of the roof sheets. The adjoining ends of adjacent beams are rigidly connected by members 20 extending longitudinally of the 40 car beneath the roof sheets. Each of these members is formed with a plate portion 21 and downwardly extending marginal flanges 22 and is rigidly secured to the lateral flanges 18 of an adjacent beam by rivets 23 45 passing through the latter and the plate 21 of the member. Inasmuch as the members 20 extend beneath the carline portions they form with the latter structures of box-like 50 sections, thereby strengthening the carline portions and rigidifying the roof structure as a whole. The arrangement of the members 20 is such that a chain, rope or other suitable means capable of cooperating with a load lifting device may be conveniently 55 supported thereby.

Extending transversely of the car beneath the roof sheets are a plurality of members 24 respectively connected to the beams 15. One or more of these members may be associated with each beam and each of them is 60 formed with a plate portion 25 and downturned marginal flanges 26. The members are preferably secured to the beams by rivets 27 which pass through the lateral flanges of 65 the latter and the plate portions 25 of the

former. The central portion of each of the members 24 is preferably bowed or arched downwardly to provide a space therebetween and the adjoining portion of the adjacent roof sheet so that a chain, rope, nose 70 of a hook, or other suitable means capable of supporting a load lifting device may be inserted therein.

From the foregoing it will be perceived 75 that the beams 15 are rigidly connected to each other so that forces transmitted to them from the means for supporting load lifting devices will be more or less evenly distributed throughout the roof structure and not concentrated in localized areas. Furthermore, the means employed for connecting the beams serve to rigidify the carline portions of the roof and are adapted to serve as supports for load lifting devices. It will 80 also be perceived that inasmuch as the beams 15 are located on the outside of the roof sheets the revenue earning space of the 85 car is not impaired.

90 In Figures 6 to 9 inclusive the invention is shown as applied to a roof employing separate carlines instead of carlines formed integrally with the roof sheets. In this form of the invention the roof sheets 3 are provided with upturned flanges 28 and the adjacent flanges of adjoining roof sheets are 95 embraced by the carlines designated by the reference numeral 29. Each of these carlines is of U-shape and has downwardly extending legs 31 which terminate in laterally projecting flanges 32 arranged in overlapping 100 relation to adjacent portions of the roof sheets. The carlines and roof sheets may be conveniently connected by rivets 33 passing through the flanges 28 and the legs 31.

105 In order that the major portion of the flanges 18 of the beams 15 may be in engagement with the roof sheets 3 they are offset upwardly as at 34 to pass over the lateral flanges 32 of the carlines. Instead of employing members 20 for connecting the adjoining ends of adjacent beams, the latter may be secured together by rivets 35 which 110 pass through the flanges 19 of the beams and the legs 31 of the carlines. In this manner the separate beams will function as a single one. The supporting members for the load lifting devices are of the same design in this 115 form of the invention as in the form illustrated in Figures 1 to 5 inclusive and they are associated with the beams in the same manner.

120 It will be readily appreciated that the invention is not limited in its application to roof structures of the particular types illustrated in the drawings and that various changes or modifications may be made without departing from the spirit of the invention as defined by the following claims.

I claim:

1. A roof for railway cars involving roof sheets, upstanding carline portions, a longitudinally disposed beam extending between said carline portions in overlapping relation to the outer face of an adjacent roof sheet, and a member extending transversely of the car beneath the roof sheets, said member being rigidly secured to said beam and constituting means for supporting a load lifting device. 70
2. A roof for railway cars involving roof sheets, carline portions extending upwardly above said roof sheets, a beam extending longitudinally of the car between said carline portions and above said roof sheets, said beam having portions disposed in overlapping engagement with said carline portions, and members extending transversely of the car beneath the roof sheets, each of said members being rigidly secured to said beam and constituting means for supporting a load lifting device. 80
3. A roof for railway cars involving roof sheets, upstanding carline portions, a beam extending longitudinally of the car between said carline portions above the roof sheets, said beam having lateral flanges rigidly secured to the roof sheets, and members extending transversely of the car beneath the roof sheets, each of said members being rigidly secured to the flanges of the beam and constituting means for supporting a load lifting device. 90
4. A roof for railway cars involving roof sheets, carline portions of inverted channel shape extending above said roof sheets, a longitudinally disposed beam extending between said carline portions and rigidly secured to an adjacent roof sheet in overlapping relation to the outer face of the latter, and members extending transversely of the car beneath the roof sheets, each of said members being rigidly secured to said beam for supporting a load lifting device. 100
5. A roof for railway cars involving roof sheets integrally formed with upwardly extending carline portions, a beam extending longitudinally of the car between said carline portions above the roof sheets, said beam having portions disposed in overlapping engagement with said carline portions, and members extending transversely of the car constituting means for supporting a load lifting device, each of said members being rigidly secured to the beam and an adjacent roof sheet. 110
6. A roof for railway cars involving roof sheets, carline portions extending upwardly above said roof sheets, a beam extending longitudinally of the car between said carline portions and above the roof sheets, said beam being of inverted channel shape and having oppositely disposed laterally projecting flanges, said flanges being rigidly 120
- secured to the adjacent roof sheet, and members extending transversely of the car beneath the roof sheets, each of said members being rigidly secured to the flanges of said beam and constituting means for supporting a load lifting device. 130
7. A roof for railway cars involving roof sheets, carline portions projecting above said roof sheets, a longitudinally disposed beam extending between said carline portions above the roof sheets, and members extending transversely of the car beneath the roof sheets and rigidly secured to said beam, each of said members having a portion disposed in spaced relation to the adjacent roof sheet whereby a load lifting device may be inserted between the roof sheet and said portion to be supported by the latter. 140
8. A roof for railway cars involving roof sheets, carline portions extending upwardly above said roof sheets, a plurality of beams extending longitudinally of the car above the roof sheets and respectively disposed on opposite sides of said carline portions, and means extending longitudinally of the car beneath said roof sheets for connecting adjoining ends of adjacent beams, and a member rigidly secured to each beam and extending transversely of the car beneath the roof sheets, said member constituting means for supporting a load lifting device. 150
9. A roof for railway cars involving a plurality of roof sheets, carline portions extending upwardly above said roof sheets, beams extending longitudinally of the car above the roof sheets and respectively disposed on opposite sides of said carline portions, each of said beams having laterally projecting flanges, means extending beneath said carline portions for rigidly connecting adjoining ends of adjacent beams, and members extending transversely of the car beneath said roof sheets, each of said members being rigidly secured to the lateral flanges of an adjacent beam and constituting means for supporting a load lifting device. 160
10. A roof for railway cars involving a plurality of roof sheets, inverted channel-shaped carline portions projecting upwardly above said roof sheets, beams extending longitudinally of the car above said roof sheets on opposite sides of said carline portions, members extending longitudinally of the car beneath the roof sheets and rigidly secured to adjoining ends of adjacent beams, said members forming with the carline portions structures of box-like section, and members extending transversely of the car beneath the roof sheets and rigidly secured to said beams, said longitudinally and transversely extending members respectively constituting means adapted to support a load lifting device. 170
11. A roof for railway cars involving a 180

- plurality of roof sheets, carline portions of inverted channel shape projecting upwardly above said roof sheets, beams extending longitudinally of the car above said roof sheets on opposite sides of said carline portions, each of said beams being of inverted channel shape and having oppositely disposed laterally projecting flanges secured to the roof sheets, members extending longitudinally of the car beneath said carline portions for rigidly connecting adjoining ends of adjacent beams, said longitudinal members forming with the carline portions structures of box-like section, and transversely extending members disposed beneath the roof sheets and respectively secured to the lateral flanges of said beams, each of said longitudinally and transversely extending members constituting means adapted to support a load lifting device.
12. A roof for railway cars involving roof sheets having marginal flanges along their side edges, carlines extending upwardly above said roof sheets and respectively secured to the adjacent marginal flanges of neighboring roof sheets, a beam extending longitudinally of the car above said roof sheets between said carlines, and members extending transversely of the car beneath the roof sheets, each of said members being rigidly secured to said beam and constituting means for supporting a load lifting device.
13. A roof for railway cars involving roof sheets, carlines extending upwardly above said roof sheets and rigidly secured to adjoining portions of neighboring roof sheets, each of said carlines having a laterally extending flange, a beam extending longitudinally of the car above said roof sheets between said carlines and resting upon the lateral flanges of the latter, and members extending transversely of the car beneath the roof sheets, each of said members being rigidly secured to said beam and constituting means for supporting a load lifting device.
14. A roof for railway cars involving roof sheets, carlines extending upwardly above the roof sheets and rigidly secured to adjacent portions of neighboring roof sheets, each of said carlines having downwardly extending legs terminating in lateral flanges, beams extending longitudinally of the car above said roof sheets on opposite sides of said carlines, each of said beams being rigidly secured to adjacent legs of neighboring carlines and resting upon the lateral flanges of the latter, and members extending transversely of the car beneath the roof sheets, each of said members being rigidly secured to an adjacent beam and constituting means for supporting a load lifting device.
15. A roof for railway cars involving a plurality of roof sheets, carlines extending upwardly above the roof sheets and rigidly secured to adjoining portions of neighboring roof sheets, each of said carlines being provided with laterally extending flanges, beams extending longitudinally of the car above said roof sheets on opposite sides of said carlines, each of said beams being of channel shape and having laterally extending flanges rigidly secured to an adjacent roof sheet and resting upon the lateral flanges of neighboring carlines, and members extending transversely of the car beneath the roof sheets, each of said members being rigidly secured to the lateral flanges of an adjacent beam and constituting means for supporting a load lifting device.
16. A roof for railway cars involving roof sheets, a beam member rigid with the roof and disposed in overlapping relation to the outer face of an adjacent roof sheet, and a member disposed beneath the roof sheets and rigidly secured to said beam, said member constituting means for supporting a load lifting device.
17. A roof for railway cars involving a roof sheet, carline means, a beam extending longitudinally of the car in overlapping relation to the outer face of said roof sheet, and a member disposed beneath the roof sheets and rigidly secured to said beam, said member having a portion disposed in spaced relation to the roof sheets and constituting means for supporting a load lifting device.
18. A roof for railway cars involving roof sheets, carline means, a beam rigidly secured to said carline means and extending longitudinally of the car in overlapping relation to one of said roof sheets, and a member disposed beneath said last named roof sheet and rigidly secured to said beam, said member constituting means for supporting a load lifting device.
- In testimony whereof I affix my signature.
- EARL R. SWANSON.
